Patented June 17, 1919.

Inventor:
William J. Sweeney,
By his Attorney,
Leo. McNeath

UNITED STATES PATENT OFFICE.

WILLIAM J. SWEENEY, OF EAST ORANGE, NEW JERSEY.

DESIGN FOR A FLAG, PENNANT, OR SIMILAR ARTICLE.

53,471.

Specification for Design. Patented June 17, 1919.

Application filed February 11, 1918. Serial No. 276,444. Term of patent 3½ years.

To all whom it may concern:

Be it known that I, WILLIAM J. SWEENEY, citizen of the United States, residing at East Orange, county of Essex, and State of New Jersey, have invented a new, original, and ornamental Design for Flags, Pennants, or Similar Articles, of which the following is a specification, reference being had to the accompanying drawing, forming part thereof.

The drawing represents a face view of the pennant showing my new design.

I claim:

The ornamental design for a flag, pennant, or similar article, as shown.

WILLIAM J. SWEENEY.

Witnesses:

GEO. WM. MIATT,
DOROTHY MIATT.
